ATTORNEY

UNITED STATES PATENT OFFICE

FRANK A. SCHNEIDER, OF SAN FRANCISCO, CALIFORNIA

OIL BURNER

Application filed December 4, 1928. Serial No. 323,669.

This invention relates to improvements in oil burners and more particularly to a simply constructed, inexpensive and generally improved atomizer and burner tip arrangement which will cause a thorough and effective admixture of the oil with the steam or other fluid discharged under pressure with the oil from the burner tip, and which will also thoroughly atomize this admixed fuel and cause atomized fuel to have a rapid spiral flow out through the burner tip. This treatment of the oil and steam provides for a substantially conical jet of fuel at the burner tip, and gives the same effective form to the flame. The construction and arrangement of the atomizer and burner tip provide for a hot, effective flame with a comparatively low fuel consumption, and without use of rotating parts.

An object of the invention is to provide an oil burner of the character described which will be strong, durable and require little or no servicing over long periods of use.

A further object is to provide an oil burner atomizer of the character described which will not readily clog and which may be readily and easily taken out of and reassembled in the burner for cleaning purposes, this element being simple and compact as to form, and provides for a thorough breaking up of the oil and as thorough an admixture of the steam or air with the oil. Another object is to provide a non-rotating, small, and compact atomizer of the character described in which the steam or other fluid is fed under pressure thereto, and so treated thereby, that it will follow a spiral path in the atomizer and act upon the oil stream entering the atomizer so as to thoroughly break up the oil admixed therewith and cause a large forceful jet of properly atomized fuel to be discharged from the burner.

With the above mentioned and other objects in view, the invention consists in the novel construction and combination of parts hereinafter described, illustrated in the accompanying drawings, and set forth in the claims hereto appended, it being understood that various changes in the form, proportion,

size and minor details of construction within the scope of the claims may be resorted to without departing from the spirit or sacrificing any of the advantages of the invention.

55 Referring to the drawings:

Fig. 1 represents a fragmentary longitudinal sectional view of the oil burner of this invention taken on the plane of line 1—1 of Fig. 3.

Fig. 2 represents a front end elevation of the burner.

Fig. 3 represents a sectional view taken on the plane of line 3—3 of Fig. 1, showing the front face of the atomizer.

Fig. 4 represents a sectional view taken on the plane of line 4—4 of Fig. 1, showing the rear face of the atomizer.

Fig. 5 represents a sectional view taken on the plane of line 5—5 of Fig. 1.

Fig. 6 represents a side elevation of the atomizer.

The embodiment of the invention shown in detail in the accompanying drawings, comprises a steam pipe 1, within which is mounted an oil pipe 2 of considerably less diameter than the steam pipe. One end of the steam pipe is screwed into a nipple 3 on a fitting generally designated 4, and the end of the oil pipe is likewise screwed into a nipple 5 on said fitting. On one side of the fitting is a nipple 6 which provides for connection of the fitting with a source of supply of steam, air, or other fluid such as may be used with the oil, as is customary in oil burners, said nipple leading into a chamber 7 which communicates with the inner open end of the steam pipe 1. A similar oil line nipple 8 is provided on the fitting and leads into a chamber 9 which communicates with the open inner end of the oil pipe 2.

90 A sleeve 10 is screwed onto the outer end of the steam pipe so as to project forwardly from the pipe, and a flanged sleeve 11 is screwed on the outer end of the sleeve 10 so that its flange 12 will engage and hold in place, a disc-like burner tip 13. The rear face of the tip plate 13 engages the annular wall 14 of a cup member 15 seated tight in the outer end of the sleeve 10, the bottom

or back 16 on said cup engaging and closing the outer end of the pipe 1. Said cup 15 has an inward extension 17 which is cored out and threaded to screw onto the outer end of the oil pipe 2.

5 An oil passage 18 extends through the extension 17 into a circular depression or counter-bore 19 formed centrally in the bottom of the cup. A conical valve seat 20 is provided at the intake end of said passage 18. A needle valve 19' is adapted to cooperate with the seat 20 and is carried on a valve rod 21 which extends through the oil pipe fitting 4 and stuffing box 22. Parts of the rod and stuffing box are screw threaded as at 23 so that the valve 19 may be opened and closed on turning the valve handle 24.

10 Steam passes into the cup 15 through openings 25 formed in a circular series in the back or bottom 16 of the cup.

15 Steam passes into the cup 15 through openings 25 formed in a circular series in the back or bottom 16 of the cup.

20 The especially constructed atomizer element of this invention is mounted in the cup 15 and is in the form of a small, circular disc or plate 26, the periphery of which engages the inner side of the annular wall 14, the back of which seats against the bottom 16 of the cup, and the front face of which seats against the rear face of the burner tip plate 13.

25 In the front face of the atomizer disc 26 is a spiral groove 27 terminating in the center of the disc in the form of a nearly circular well or depression 28. An oil intake opening 29 is formed in the atomizer disc 26 so as to open into the well 28 near one side of said well, or better, near the inner end of the groove 27. Steam or air intake openings 30 are formed in the disc 26 so as to open at spaced points in the groove 27 near the outer end of the groove, or at a point considerably removed from the oil opening 27, whereby the steam will follow a spiral path before encountering the oil stream entering at the opening 29. The groove 27 is closed on its outer side by the rear face of the plate 13, and there is formed in this way, a spiral passage which opens into the well or depression 28. Through the center of the plate 13 is a burner orifice 32 of a double inverted cone or hour glass shape, which registers with the well or depression 28 and thereby provides for the discharge from the burner of a large, swirling, conical oil jet.

30 Steam from the pipe 1 passes through the openings 25 into the openings 30 formed in the disc 26, with which openings 30, the said openings 25 register. The openings 25 on the bottom of the cup 15 are so arranged that in the assembly, by placing the disc 26 into the cup 15, the same may be readily aligned in the usual manner to bring the openings 30 in registry with the openings 25 of the cup 15.

35 The oil and steam are both delivered un-

der pressure, to their respective pipes of the burner, the steam pressure being higher than the oil pressure. The steam entering the groove 27 of the atomizer, causes it to rapidly follow a spiral path and this spiral steam stream on encountering the oil discharging from the opening 29 into the well 28, causes not only a thorough admixing of the steam therewith, but also causes the ensuing mixture to be given a rapid helical motion as it is discharged out through the burner orifice. In this way a large, forcible jet of fuel in conical form, is discharged with the oil thoroughly broken up or atomized. No rotating parts are necessary due to the special atomizer construction in order to thoroughly break up the oil and to effectively admix the steam therewith. This simple and inexpensive construction is further advantageous, because it will provide a great economy in fuel while causing a large, hot flame to be produced at the burner. It will be noted that the burner construction, at the top is such that the atomizer is effectively clamped in place, and will not rotate. This construction of the burner at the top, also facilitates the assembling and disassembling of the apparatus.

I claim:

1. An oil burner including a tubular body, a burner tip having a burner orifice therein, which tip closes the outer end of the tubular body, an atomizer disc mounted in and engaging at its periphery the tubular body and bearing on its outer face against the inner side of said burner tip, said disc having a spiral groove in the face thereof which is engaged with said tip, and having a portion of said groove in registration with said orifice, said disc having openings therethrough into said groove, means for feeding oil to one of said openings nearest to the center of the spiral, and means for feeding steam to the other of said openings nearer the outer periphery of said spiral, the said openings for the oil being offset relatively to the burner orifice and relatively to the center of the spiral, and being in the path of the stream of steam passing through said spiral.

2. An oil burner including a burner tip disc having a burner orifice extending therethrough, an atomizer disc having one face engaged with the rear side of said burner tip disc, which face is provided with a spiral groove in part in registration with said orifice, said disc having an oil discharge port therein offset relatively to the burner orifice, and offset relatively to the center of the spiral and located with its mouth adjacent to the face of the groove; and means to pass a stream of steam into the groove so that said stream of steam is given an increasing angular velocity directly across the oil discharge port.

3. An oil burner including a burner tip member having a burner orifice extending through it, an atomizer member having a spiral groove in one face thereof and intake openings extending through it at spaced points into said groove, means for holding said atomizer member against the burner tip member so that the latter will cover and close the outer side of the groove except for a portion of the groove, which portion is in registration with said orifice, the opening nearest to the inner end of the groove being an oil discharge port, and being offset relatively to the burner orifice, and being in the path of the fluid flow in the groove; and means for delivering steam into the other of said openings so that a jet of steam is passed with increasing angular velocity directly across the said port.
4. An oil burner including a burner tip member having a burner orifice extending through it, an atomizer member having a spiral groove in one face thereof and intake openings extending through it at spaced points into said groove, means for holding said atomizer member against the burner tip member so that the latter will cover and close the outer side of the groove except for a portion of the groove, which portion is in registration with said orifice, means for delivering oil into one of said openings, and means for delivering steam into the other of said openings, the oil intake opening being located close to the inner end of said groove and being eccentric relatively to the burner orifice, said oil intake opening being offset relatively to the center of the spiral, and located with its mouth adjacent to the face of the jet and said steam intake opening being located at a point considerably spaced from said end of the groove.
5. An oil burner including a burner tip disc having a fuel outlet orifice extending through it and an atomizer disc having one face lying against the rear side of said burner tip disc, which face is provided with a spiral groove, the inner end of which groove is located in the approximate center of said disc and is in registration with said orifice, said atomizer disc having an oil intake opening therein leading into said groove near said inner end of the groove, and offset relatively to the orifice said oil intake opening being offset relatively to the center of the spiral, and located with its mouth adjacent to the face of the jet said atomizer disc also having a fluid intake opening therein leading into said groove at a point considerably spaced from the inner end of the groove.
6. In an oil burner a disc having one face thereof provided with a spiral groove, the inner end of which groove is located in the approximate center of the disc, and having

an oil intake opening adjacent the inner end of the groove and offset from the center of the spiral, and having a fluid intake opening leading into said groove at a point considerably spaced from the inner end of the groove; and a burner tip to cover said groove, said tip having an outlet orifice in registry with the center of the spiral groove.

7. In an oil burner a disc, a burner tip to cover a face of the disc, said burner tip having an outlet orifice thereon, said disc having an oil discharge port thereon, means on the face of the disc to pass a stream of steam with increasing angular velocity directly across the oil discharge port, said oil port being offset relatively to the center of the burner orifice.

8. In an oil burner a disc, a burner tip to cover a face of the disc, said burner tip having an outlet orifice therethru, said disc having an oil discharge port thereon offset relatively to the center of the orifice, said disc also having inlet ports for another fluid spaced from the oil port and a passage arranged to conduct the fluid from the fluid inlet ports to the orifice and to give to the stream of fluid in the passage an increasing angular velocity directly across the oil discharge port.
